Primary Examiner — Natasha Vujcic(74) *Attorney, Agent, or Firm* — Barnes & Thornburg LLP(57) **CLAIM**

What is claimed is, the ornamental design for a luminaire, as shown and described.

DESCRIPTION

FIG. 1 is a perspective view as viewed from below of the luminaire showing our design;

FIG. 2 is a perspective view as viewed from above thereof; FIG. 3 is a right side elevational view thereof, where the opposite, left side side elevational view is a mirror of this view and, therefore, has been omitted;

FIG. 4 is a front elevational view thereof, where the rear elevational view is a mirror of this view and, therefore, has been omitted;

FIG. 5 is a top plan view thereof; and,

FIG. 6 is a bottom plan view thereof.

The broken lines in the drawings illustrate portions of the Luminaire which form no part of the claimed design. The luminaire is shown with symbolic break lines along its dimensions. The appearance of any portion of the luminaire between the break lines forms no part of the claimed design. The luminaire is not limited to the scale shown herein.
